SVERRE SANDBERG, OF DRAMMEN, NORWAY, ASSIGNOR TO AKTIESELSKAPET NORSK ALUMINIUM COMPANY, OF OSLO, NORWAY.

METHOD AND APPARATUS FOR DETERMINING THE DIP OF AERIAL LINES.

Application filed May 19, 1925, Serial No. 31,433, and in Norway December 8, 1923.

In the construction of aerial lines, preferably electric lines it is desirable to have the individual stretches of the line between the points of suspension (masts) as tight as possible, i. e., with a minimum sag or dip, but on the other hand a certain maximum stress of the line must not be exceeded.

My invention relates to a method and apparatus for quickly determining the correct dip of the line to be allowed between any two points of suspension.

My method is based on the fact that a line when freely suspended between two points of suspension, forms a catenary, which because the cable is composed of unit lengths of equal weight is approximately a parabolic curve determined by the formula:

$$f = \frac{gl^2}{8H} \quad (I)$$

the derivation of which is found in "Luegers Lexikon der gesammten Technik vol. IV, page 712" in which f is the dip, g the weight of a length unit of the line (cable), l the length of the span between the points of suspension, and H the tension of the line.

If a part of a line thus suspended is given a quick tap at a point near either of the points of suspension, there will thereby be started a transverse wave travelling towards the other point of suspension, which when reflected from this point will return to the point of suspension from which it started.

The time this transverse wave takes to travel both ways (i. e., the double span width or $2l$) is designated by t seconds.

According to the law found by Newton in the year 1687

$$v = \sqrt{\frac{E}{d}} \quad (II)$$

the derivation of which is found in "Luegers Lexikon der gesammten Technik vol. IV, page 712" in which v is the velocity of the wave, and is dependent upon the coefficient of elasticity E of the material and its density d .

I may here consider the density as uniform, the waves being practically wholly transverse. This is of importance in so far as in a transverse wave only the elasticity of form is involved, and not the elasticity of volume.

If I introduce into equation (II), the

ratio between the stress δ and the variation of form ξ : i. e.;

$$E = \frac{\delta}{\xi}$$

and instead of the stress, the corresponding tension H and the cross section a , i. e.;

$$H = \delta \cdot a$$

$$\delta = \frac{H}{a}$$

This gives:

$$v = \sqrt{\frac{\delta}{d}} = \sqrt{\frac{\xi a}{d}}$$

$$\text{or } v^2 d = \frac{H}{\xi a}$$

$$H = v^2 a \xi d \quad (III)$$

If I insert, instead of the unit weight g in equation I, the cross section a and density d , I obtain,

$$q = ad$$

$$f = \frac{adl^2}{8H}$$

$$f \cdot 8H = adl^2$$

$$H = \frac{adl^2}{8f} \quad (IV)$$

By combining equations III and IV, I obtain, by equaling the value of f ,

$$v^2 a \xi d = \frac{adl^2}{8f}$$

$$f = \frac{l^2}{8v^2 \xi}$$

Finally I insert in this equation the time

$$t = \frac{2l}{v}$$

$$l = \frac{tw}{2}$$

$$l^2 = \frac{t^2 w^2}{4}$$

and obtain

$$f = \frac{t^2 v^2}{4} = \frac{t^2}{32\xi} \quad (105)$$

This equation gives the relation between the dip and the space of time used by the

transverse wave to travel back and forth. The fraction—

$$\frac{1}{32\xi}$$

has by experiments been found to be constant for the various materials as copper, aluminitium and the like.

Instead of starting from the formula of Newton I may also start from the formula given for the velocity of waves by the English scientist Professor Tait, viz:

$$v = \sqrt{\frac{F}{\delta}},$$

the derivation of which is published in his "Dynamics", London 1895 in which F is the tensional stress or strain in the line, and δ the mass of a length unit of the line.

When this formula is combined with the Formula (I) in a similar manner to the foregoing, I obtain the following equation for the dip of the line:

$$f = \frac{g}{32\xi} \cdot t^2$$

wherein ξ is a constant depending on the form-elastic properties of the material used for the line, and g is the acceleration due to gravity.

Thus also in this case I get a formula for the dip of the line between the two points of suspension expressed as a product of a constant (different for each particular material) and the square of the time used by the transverse wave.

This gives a means for making a table, giving for seconds and fractions of seconds observed, the corresponding dips, so that it is only necessary to observe the time used for the vibration to travel back and forth, to read off direct the most desirable dip of the span in question. As the waves pass back and forth several times, I may, if desired, obtain a greater accuracy by repeating the time observations and taking the average thereof.

In accordance with my invention I use for

observing the dip, an apparatus in the form 50 of a stop watch of known construction, which is provided with a dial having a division or scale, giving directly the dip for the line material in question, corresponding to the time observed by the aid of the stop 55 mechanism.

On the accompanying drawing, is shown, by way of example, such a stop watch as used for this invention.

In the drawing; the outer scale 1, is the 60 usual scale of minutes and fractions thereof. The inner scale 2, however, is arranged in conformity with the present invention, so that the position of the hand 3 directly gives the dip corresponding to the observed time, 65 according to the formula obtained above i. e., as a product of the square of the time observed, and a constant which depends upon the material used for the aerial line in question.

It will be understood that this apparatus may be used to determine the dip in mounting the line as well as to control lines already built.

I claim:—

1. A method of determining the dip of an aerial line freely suspended between two points, comprising, starting a transverse wave in the line at one suspension point, and utilizing the time required by such wave to 80 travel back and forth between the points of suspension, by the aid of a scale, to determine the dip in the line as a function of the time of travel of the wave.

2. A method of determining the dip of 85 an aerial line freely suspended between two points, comprising, starting a transverse wave in the line and utilizing the time required by such wave to travel back and forth between the points of suspension, by 90 aid of a scale, to determine the dip in the line as a product of the square of the time of travel of the wave and a constant depending on the material of the line.

In testimony whereof I have signed my 95 name to this specification.

SVERRE SANDBERG.
